US00D930687S

(12) **United States Design Patent** (10) **Patent No.:** **US D930,687 S**
Butcher et al. (45) **Date of Patent:** **** Sep. 14, 2021**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Gary Butcher**, San Jose, CA (US);
Jonathan P. Ive, San Francisco, CA (US); **Chanaka Karunamuni**, San Jose, CA (US); **Alessandro Francesco Sabatelli**, San Francisco, CA (US); **Christopher Daryl Soli**, Mountain View, CA (US); **Wan Si Wan**, Sunnyvale, CA (US)

(73) Assignee: **Apple Inc.**, Cupertino, CA (US)

(**) Term: **15 Years**

(21) Appl. No.: **29/756,733**

(22) Filed: **Oct. 30, 2020**
